(57) **CLAIM**

The ornamental design for a mini bike, as shown and described.

DESCRIPTION

FIG. 1—is a front perspective view of the mini bike;

FIG. 2—is a front view of the mini bike;

FIG. 3—is a rear view of the mini bike;

FIG. 4—is a right side view of the mini bike;

FIG. 5—is a left side view of the mini bike;

FIG. 6—is a top view of the mini bike;

FIG. 7—is a bottom view of the mini bike; and,

FIG. 8—is a rear perspective view of the mini bike.

The broken lines illustrate portions of the mini bike that form no part of the claimed design.
